(57) **CLAIM**

The ornamental design for a combination digital and analog timepiece face, as shown and described.

DESCRIPTION

FIG. 1 is a front elevational view of a first embodiment of a combination digital and analog timepiece face

FIG. 2 is a front elevational view of the first embodiment of a combination digital and analog timepiece face

FIG. 3 is a front elevational view of the first embodiment of a combination digital and analog timepiece face

FIG. 4 is a front elevational view of a second embodiment of a combination digital and analog timepiece face; and,

FIG. 5 is a front elevational view of a third embodiment of a combination digital and analog timepiece face.

The broken lines in the drawings represent environmental subject matter and form no part of the claimed invention. The timepiece face is flat. The time of 5:52 depicted in the figures is merely representative of a single time of day.
